[57] CLAIM

The ornamental design for a combined hair dryer and holder, as shown and described.

DESCRIPTION

FIG. 1 is a top right perspective view of a combined hair dryer and holder, the cords being depicted discontinuously for ease of illustration; and

FIG. 2 is a top left perspective view with the dryer disengaged; and

FIG. 3 is a right side elevational view with the dryer disengaged; and

FIG. 4 is a bottom plan view thereof.

FIG. 1

FIG. 2
